HEAD FRAME FOR SUPPORTING
EYESHIELDSLeo Roe Cornell, Berkeley, Calif., assignor of one-
fourth to Gerold B. Lenz

Application March 27, 1938, Serial No. 71,241

8 Claims. (Cl. 2-8)

My invention relates to head frames and more particularly to headgear for supporting eyeshields or goggles.

Those engaged in occupations hazardous to the eyes, such as welding, are required by safety regulations, as well as by common necessity, to protect their eyes from injury by the use of eyeshields or goggles. It is obviously important that these shields be firmly supported and held against dislodgment during the course of the work and that they be easily and readily removed from obstructing normal vision when the wearer requires. Heretofore the devices for supporting the shields have been cumbersome in operation, particularly in that the operator must free his hands of equipment in order to place the goggles in shielding position. My invention, however, overcomes this difficulty by a novel arrangement of structure which permits the placement of the goggles in shielding position by a mere nod of the wearer's head.

It is an important object of my invention, therefore, to provide improved means for supporting eyeshields.

Other objects of my invention are: To provide a head frame for supporting eyeshields, which is of simple construction and which can be economically manufactured; to provide in such a device means whereby the size of the frame may be varied to accommodate different head sizes; to provide in a head frame of the class described means whereby the eyeshields may be moved from closed to retracted position or vice versa, with reference to the face of the wearer, without disturbing the normal position of the frame on the wearer's head; to provide in such a device means for resiliently maintaining the eyeshields in either retracted or closed position, and to provide a lightweight and sturdy structure of the class described.

The invention possesses numerous additional objects and advantageous features, some of which, with the foregoing, will become apparent upon perusal of the following description of my invention. It is to be understood, however, that I do not limit myself to the particular species of invention, since I may adopt variant embodiments thereof within the scope of the claims.

Referring to the drawing:

Figure 1 is a plan view of a head frame incorporating my invention, the goggles being shown in retracted position.

Figure 2 is a side elevation thereof.

Figure 3 is a sectional elevational view similar

to Figure 2 but with the goggles in shielding or closed position.

Figure 4 is a fragmentary view, in elevation, looking in the direction of arrow 4 of Figure 2, and illustrating the structure for varying the size of the headband and strap.

In terms of broad inclusion, the apparatus of my invention comprises a headband adapted to encircle the head of the wearer. Means is provided for normally positioning said band on the wearer's head, and further means is supplied for varying the size of said band and said positioning means, whereby different head sizes may be accommodated. Additional structure carried by said band is also provided for supporting the eyeshields, whereby they may be moved from retracted to closed position or vice versa, with respect to the face of the wearer, and means is provided for resiliently maintaining the shields in said retracted or closed positions.

With reference to the preferred construction illustrated by the drawings, my device comprises a headband 2 adapted to encircle the head of the wearer and preferably formed of a relatively thin strip 3 of light-weight flexible material such as sheet fibre, capable of being bent into a loop or band and of readily shaping itself to the head contours to promote comfort and facilitate placement and removal. Strip 3 adjacent its opposite ends is provided with elongated apertures 4 which are adapted to fall into alignment when the strip ends are brought into overlapping relationship. In such position the ends of the strip are secured together by a clamping structure comprising a relatively thin backplate 5 carrying a pair of spaced lugs or bolts 6 which are adapted to extend through the aligned apertures 4 and receive the threaded clamp nuts 7. It is obvious that upon loosening the nuts 7, the size of the band 3 may be varied to accommodate various head sizes, and this by simply increasing or decreasing the amount of overlap of the strip ends, as limited by the length of the apertures.

It is to be understood that I do not wish to limit myself to the particular form of clamping structure shown, since various well-known types thereof will readily suggest themselves to those skilled in the art.

In stamping, cutting or otherwise forming the strip 3, I have found it to be of advantage to so shape the same that when the ends thereof are brought together to form the loop or band 3 the rear portion of the band curves downwardly and outwardly as shown in Figure 2. When so shaped, the rear portion of the band is normally posi-

tioned low on the wearer's head and is not easily displaced or dislodged by any downward pull applied to the front thereof.

Means is provided for normally positioning the headband on the head of the wearer, which comprises an arcuate crown strap 8, one end of which is suitably secured in any well-known manner to the front of the headband, and the other end of which, being provided with a pair of elongated apertures 9 so spaced that the lugs 6 of the clamping structure pass therethrough, is secured to the back of band 3 by the mere tightening of the clamp nut on the lugs. Thus it is obvious that the length of the crown strap, like the headband, may be varied within the limits of the apertures 9 to accommodate various head sizes.

A pair of parallel brackets 10, riveted or otherwise fixedly secured to opposite sides of the headband and extending tangentially therefrom, are provided, which pivotally support, on their outer ends, by means of the pivot screws 11 a pair of arms 12. These arms in turn are removably connected at their distal portions by means of set screws 13 to the wings 14 of a pair of goggle frames 15, each of which carries a lens or eyeshield 16. The frames 15 are preferably connected in such manner that they may be moved relative to each other in order to permit their adjustment to the face of the user. For this purpose I provide an adjustable clamp assembly 17 of any well-known design, and in order to facilitate such adjustment, I prefer that the supporting arms 12, as well as the brackets 10, be formed of light-weight flexible material, for instance, sheet fibre.

I prefer that provision be made for connecting the goggle frames to the arms 12 at various distances from the pivot screws 11 in order to facilitate adjustment thereof relative to the face of the wearer. For such purpose, therefore, I provide a plurality of spaced apertures 18 in the distal portions of arms 12 through which the set screws 13 may pass for securing the arms and frames together.

It is highly desirable that eyeshields or goggles during protective use be maintained in close contact at all times with the face of the wearer in order to afford the maximum protection; furthermore, that the goggles be removable from obstructing normal vision without the necessity of disturbing the entire headgear, and also that they be restrained from uncontrolled movement in their respective closed or retracted positions. My invention, therefore, includes means for resiliently maintaining the goggles in either closed or retracted position. This means preferably comprises a pair of coiled springs 19 having one end thereof secured to the lugs 20 on arms 12 and the other end to the lugs 21 on brackets 10.

It will be observed that the positioning of the springs on the brackets and arms is such that when the goggles are in closed position as shown in Figure 3 the spring will resiliently maintain the same in contact with the face of the wearer, and that when in retracted position as shown in Figure 2 the goggles will be similarly held against uncontrolled movement, with maximum retraction limited by the lugs 22 formed on brackets 10 which provide a stop against which the shoulders 23 of arms 12 rest.

I have found that one of the particular advantages of the headgear of my invention lies in the ease and simplicity with which the goggles may be swung from retracted to closed position

or from closed to retracted position. This can be done by a mere nod of the head, thereby leaving the hands of the wearer free for the handling of equipment or supplies with which he is working.

I claim:

1. In a device of the class described, a headband comprising a strip of flexible material formed in a loop and adapted to encircle the head of the wearer, means connected with said loop and positioned to engage another portion of the head of the wearer whereby the band is maintained thereon in normal position, a pair of brackets projecting from said loop, an arm pivotally mounted on each bracket and movable into each of two angular positions with respect to said brackets, a shield secured to said arms for protecting the face of the wearer, and resilient means interposed between said arms and said brackets for maintaining said arms in either of 20 said positions.

2. In a device of the class described, a headband comprising a strip of flexible material formed in a loop and adapted to encircle the head of the wearer, means connected with said loop and positioned to engage another portion of the head of the wearer, a pair of brackets projecting from said loop, an arm pivotally mounted on each bracket and movable into each of two angular positions with respect to said brackets, 30 a shield, carried by said arms, for protecting the face of the wearer, resilient means interposed between said arms and said brackets for maintaining said arms in either of said positions, and a stop on one of said brackets for positively fixing, in one position of said arm, the angular relationship between said arm and said bracket.

3. In a device of the class described, a strip of flexible material formed in a loop and adapted to encircle the head of the wearer, a strap secured to 40 said loop and extending diametrically thereacross for engaging the head of the wearer, means for varying the size of said loop to accommodate different head sizes, a pair of brackets secured to and extending from said loop, an arm pivotally 45 mounted on each of said brackets, said arms being movable into either of two angular positions with respect to said brackets, a shield, for protecting the face of the wearer, carried by said arms, a coiled spring secured at its respective ends to a 50 bracket and an arm for resiliently holding said arms in one of their two positions, and stops on said brackets for engaging said arms and limiting the degree of movement thereof in one direction.

4. In a device of the class described, a strip of 55 flexible material formed in a loop and adapted to encircle the head of the wearer, a strap secured to said loop and extending diametrically thereacross for engaging the head of the wearer, means for independently adjusting the size of said loop and 60 the position of said strap relative to said loop to fit different head sizes, a pair of brackets secured to and extending from said loop, an arm pivotally mounted on each of said brackets, said arms being movable into either of two angular positions with 65 respect to said brackets, a shield, for protecting the face of the wearer, carried by said arms, a coiled spring secured at its respective ends to a bracket and an arm for resiliently holding said arms in one of their two positions, and stops on 70 said brackets for engaging said arms and limiting the degree of movement thereof in one direction.

5. In a device of the class described, a strip of 75 flexible material formed in a loop and adapted

5 to encircle the head of the wearer, a strap secured to said loop and extending diametrically thereacross for engaging the head of the wearer, means for adjusting the size of said loop to fit different head sizes, a pair of brackets secured to and extending from said loop, an arm pivotally mounted on each of said brackets, said arms being movable into either of two angular positions with respect to said brackets, a shield, for protecting the face of the wearer, carried by said arms, means on said arms for adjusting the position of said shield thereon, a coiled spring secured at its respective ends to a bracket and an arm for resiliently holding said arms in one of their two 15 positions, and stops on said brackets for engaging said arms and limiting the degree of movement thereof in one direction.

6. In a device of the class described, a headband comprising a strap of flexible material 20 formed in a loop and adapted to encircle the head of the wearer, means connected with said loop and positioned to engage another portion of the head of the wearer, means for supporting on said headband a shield adapted to cover a portion 25 of the face of the wearer, said shield being movable into either a closed or retracted position with respect to said face, and resilient means for maintaining said shield in each of said positions, said resilient means being of such character and 30 so disposed as to permit said shield to be moved from said retracted to said closed position or vice versa by a nod of the wearer's head.

7. In a device of the class described, a headband adapted to engage the head of the wearer, means

supported by and extending from said headband for shielding the face of the wearer, and said headband having a rear portion lying permanently in a downwardly extending plane with respect to the plane of the front portion thereof whereby said rear portion is capable of engaging the basal portion of the wearer's head in such manner as to counteract the tendency of the overhanging weight of the face-shielding means to disturb the normal position of the headband on 10 the wearer's head.

8. In a device in the class described, a head band adapted to engage the head of the wearer, a strap disposed on said head band for normally positioning the same on the head of the wearer, 15 means supported by and extending from said head band for shielding the face of the wearer, and said head band having a rear portion lying permanently in a downwardly extending plane with respect to the plane of the front portion 20 thereof whereby said rear portion is capable of engaging the basal portion of the wearer's head in such a manner as to counteract the tendency of the overhanging weight of the face shielding means to disturb the normal position of the head 25 band on the wearer's head, and a clamp associated with said head band and strap and comprising members one of which is movable relative to the other for adjustably clamping the head band and strap in overlapped relation with adjacent opposed surfaces of the head band and strap in contact with each other.

LEO ROE CORNELL.
